UNITED STATES PATENT OFFICE.

KURT A. VOGEL, OF CHICAGO, ILLINOIS.

RAZOR-SHARPENING MACHINE.

1,097,953.

Specification of Letters Patent.

Patented May 26, 1914.

Application filed February 24, 1913. Serial No. 750,148.

To all whom it may concern:

Be it known that I, KURT A. VOGEL, a citizen of the United States, residing at Chicago, Illinois, have invented certain new and useful Improvements in Razor-Sharpening Machines, of which the following is a specification.

The essential object of this invention is to provide a machine for sharpening razors, and the machine is adapted both to hold a razor or razor blade successively against a revolving honing stone and a stropping roller and to move the razor or blade lengthwise of the roller or rollers.

In the drawings, Figure 1 is an end elevation of the machine; Fig. 2 is a side elevation of the machine; Fig. 3 is a top plan view of the device for holding blades which are to be sharpened; Fig. 4 is a section on the line 4—4, Fig. 3; Fig. 5 is a view partly in section and partly in elevation of a certain device at the right-hand end of Fig. 2; Fig. 6 is a view taken at right angles to that of Fig. 5; Fig. 7 is a view of the slotted plate and the holder therefor; Figs. 8 and 9 are views at right angles to each other of the devices for supporting the inner ends of each of the blade-holders; Fig. 10 is a view of the mechanism by which the blade-holder is moved longitudinally of the machine; and Fig. 11 is a vertical sectional view of the slotted plate, shown in Fig. 7, the arm which is actuated by said slotted plate being shown in position.

The main shaft 1 extends from end to end of the machine, being supported in any suitable manner by the framework which comprises uprights or legs 2 and the cross-pieces 3. At one end of shaft 1 is pulley 4 which can rotate idly upon the shaft, but when the clutch 5 is forced toward the left, Fig. 5, and into the conical recess 6 of the pulley 4, the shaft 1 and the pulley 4 are locked together so as to rotate in unison, it being understood that the clutch-head 5 is splined upon shaft 1 at 7.

At the left-hand end, Fig. 2, the legs 2 support outwardly-extending brackets 8 connected together by an arm 9 upon which there is supported in any convenient manner the pulley 10. Said pulley is grooved and a belt 11 passes from said pulley 10 and over the pulley 12, which is fixed upon the shaft 1, and in this manner the rotation

of shaft 1 is communicated to the pulley 10. The small crank-arm 13, Figs. 2 and 10, is eccentrically connected at one end to pulley 10 by pin 14, and at the other end said arm 13 is perforated and through this perforation pin 15 passes. Said pin is retained by the ears of brackets 16 which project outwardly from the cross-head 17, which member 17 in turn is secured to the rods 18. It will be obvious, therefore, that by the devices, best shown in Fig. 10, a continuous rotation of shaft 1 and pulley 10 is adapted to be translated into longitudinal reciprocatory movement of the rods 18, which rods are slidably mounted in the framework 2, 3.

The blade-holder 19 (see Figs. 3 and 4) is supported upon the slidable frame 17, 18, and said blade-holder 19 is formed of a metal plate 20, 21 bent as best shown in section in Fig. 4. The lower half 20 of the plate may be perfectly flat, while the upper half or section 21 is bent so that one edge is adapted to come into close contact with the lower section 20, whereas, at its middle the portion 21 is spaced apart from the lower portion 20. The portions 20 and 21, therefore, act as a spring-like clamp or pair of jaws. As shown in Fig. 3, the upper portion 21 is slotted so as to divide the blade-holder into four separate units, though this number may be varied at will. A screw or bolt 22 passes through both the upper and lower sections 20 and 21, and the knob or nut 23 is adapted to screw upon the threaded end of member 22. The blade or blades 24, which are to be sharpened, are clamped between the edges of members 20 and 21 and are held in place by tightening the nut 23. The shaft 25 is held between the members 20 and 21 and said shaft 25 projects outwardly beyond the ends of the blade-holder.

The guide 26, which is merely a U-shaped piece of metal, is adapted to swing upon the member 25 as a shaft from the full line position, Figs. 3 and 4, to the dotted line position in said figures. In the full line position the guide 26 indicates the proper position for the extreme outer edge of the blades 24 which are to be sharpened, and after the blades have been properly adjusted in place and clamped between the edges 20 and 21 for sharpening, the guide 26 is swung to the dotted line position so as to be out of the

way and out of engagement with the rollers 27 and 28. Rigidly fixed to the holder 19 is the shank 29 made of spring-metal or the like, and by this shank, as will hereinafter appear, the holder itself is caused to rock upon the shaft 25 as a pivot and the extreme upper edge, Fig. 4, of the blades 24 is thus caused to rock from left to right and from right to left in said Fig. 4. Since the shaft 25 is parallel to the axes of the rollers 27, and since the shaft 25, moreover, is in such a position that the edges of the blades to be sharpened will just reach the rollers 27 and 28, it follows that the movement of the shank 29 will cause the edges, which are to be sharpened, first to engage the roller 27 and then to engage the roller 28 and since the shank 29 is made of spring metal it will be sufficiently resilient to yield when the blade comes into contact with either of the rollers, and in this manner the blade will be held tightly enough against the rollers to secure the necessary abrading effect but not so tightly as to cause the machine to bind.

25 Secured to the floor and projecting upwardly through the space between the rods 18 are standards 30, and at the upper end of each of said standards is a suitable fork 31, the height of which can be adjusted by the thumb-screw 32. Each of said forks 31 holds a slotted plate or cam 33, and through the slots 34 of said plates the outer ends of the shanks 29 are adapted to project. The standards 30 are fixed in position, but the shanks 29 will be carried from left to right, Fig. 2, and from right to left because of the longitudinal reciprocation of the framework 17, 18, upon which the blade-holders 19 are carried; and as the shanks 29 are pushed first in one direction or the other, they will be guided by the slotted plates 33. The outer ends of shanks 29, *i. e.*, the ends farthest removed from the rollers 27 and 28, will be raised as the sliding framework 45 moves in one direction, and will be lowered as it moves in the opposite direction, and conversely those edges of the blades 24 which are to be sharpened will be lowered and brought into engagement with the roller 27 as the sliding framework moves in one direction, and will be lifted and brought into contact with the roller 28 when the sliding framework moves in the opposite direction.

50 The roller 27 is supported upon a shaft 35 at one end of which is a pulley 36, and the roller 28 is supported upon a shaft 37 which carries a pulley 38. The shaft 1 carries a pair of pulleys 39 and from pulleys 39 belts 40 extend to pulleys 36 and 38, one of the belts being crossed so as to drive the rollers 27 and 28 in opposite directions. The roller 27 may conveniently be made of honing stone, and the roller 28 may be covered 55 with leather, canvas, or other stropping ma-

terial, or the rollers may be constructed in any other manner so as to enable them to perform the function of sharpening the blades 24, which are brought into contact first with one roller and then with the other. 7

In one of the legs 2 and standards 30 the shaft 41 is mounted. Said shaft 41 carries a relatively large gear 42 which meshes with and is driven by the pinion 43 upon the shaft 1. At its outer end shaft 41 is screw-threaded at 44, and the split nut 45 rides upon said threaded end 44, the two halves of said nut being normally held together and pressed into engagement with the screw threads 44 by the helical springs 46, which 80 springs 46 encircle rods 47 which are secured to the upper half of the split nut 45 and which project through suitable perforations in the lower half of said nut. Said rods 47 have caps 48 at their lower ends and the springs 46 are between the caps 48 and the under surface of the lower half of the split nut 45 so that said lower half is constantly pressed upwardly. 85

The lever 49 is pivoted at 50 to the blocks 51 which are bolted to the floor, and said lever 49 is bent at 52. Bolts or pins 53, which are rigidly secured upon each side of the lever 49, have their inner ends projecting into the groove 54 upon the clutch head 5. 90 The split nut 45 is pivoted at 55 to the arm 56, which arm is slotted at 57 and is provided with a handle 58. Through the slot 57 the pin 59 projects and said pin 59 extends from one side to the other of the yoke 60 which is at the upper end of the lever 49. The rotation of the shaft 41 causes the split nut 45 to ride slowly toward the right, Figs. 2 and 5, and when the arm 56 has been forced sufficiently far toward the right so 100 that the left-hand end of the slot 57 bears against the pin 59, the upper end of the lever 49 will likewise be carried toward the right; and as the lever 49 thus moves, the conical head 5 will be carried out of the recess 6, thus releasing the shaft 1 from the pulley 4 and stopping the operation of parts which are driven by the shaft 1. In this manner the length of time during which the sharpening process is permitted to continue 105 can be regulated at will, for the sharpening process stops whenever the split nut 45 has moved so far toward the right, Figs. 2 and 5, as to cause the release of the clutch, and the time during which the process continues 110 depends upon the distance which the split nut 45 moves from left to right. The pulley 4 may be continuously driven by a belt which is actuated by a line shaft, not shown. 115

The blades to be sharpened are placed in 120 position while the shaft 1 and the moving parts driven thereby are at rest, *i. e.*, while the clutch head 5 is unlocked from pulley 4. When it is desired to commence sharpening a blade or blades, the operator grasps the 125

130

handle 58 and pushes the arm 56 toward the left, Figs. 2 and 5. When the operator pushes the handle 58 toward the left, Figs. 2 and 5, the split nut 45 will ride over the beveled threads 44 which act as a ratchet. 5 When the nut is allowed to grasp the threads 44, the rotation of the shaft 41 will force the handle 58 toward the right, same being manually moved from right to left as desired, but when the parts are moved to the extreme left-hand position, the clutch 5 will lock the shaft 1 to the pulley 4, thus causing the machine to be driven. As the sliding framework 17, 18 is thus carried back and forth, the blades 24 have their edges first presented to the revolving roller 27 and then to the revolving roller 28, and while the edges are being so presented to the revolving roller, the holder 19 is moved lengthwise 10 with respect to the rollers 27 and 28, and the blades 24 are, therefore, moved lengthwise of the roller at the same time that their edges are being abraded by the roller. In this way 15 a true stropping motion is communicated to the blades.

In order to support the blade holder 19 upon the sliding framework 17, 18, uprights 30 61 are provided. In Fig. 2 such uprights are shown. The end uprights 61 are provided with lag screws 62 which project through said member 61 each screw 62 bearing against an end of the rod or shaft 25. To the middle upright 61 and on each side thereof are bolted the pillows 64 within 35 which the opposite ends of the shafts 25 are received. The plate 65 is secured by screws 66 to said middle upright 61, and rods 67, which have small knobs 70 secured to their upper ends, project through said plate 65. 40 At their lower ends said rods 67 carry blocks 68 which bear upon the rods 25 and serve to hold them in place, the tension being maintained by the helical springs 69, which encircle the rods 67 between the blocks 68 and plate 65. When the blade-holders 19 are 45 being assembled one end of the shaft 25 is placed between the pillow 64 and the block 68, the block 68 being lifted upwardly as the knob is pulled to the dotted line position, Fig. 8; and against the other end the lag screw 62 is tightened, and in this manner 50 each of the two holders 19 shown in the drawings is pivoted between the middle upright 61 and one of the end uprights.

55 In the drawings, particularly Figs. 2 and 3, the blade-holder 19 is depicted as being made in four sections, each of which can be tightened independently of the others, and each holder 19, therefore, is adapted to hold 60 and retain four blades of the size and shape ordinarily used in the so-called safety razors, but it is obvious that the machine is not restricted to use in sharpening safety razor blades but may, by slight obvious modifications in the shape of the holder 19, be used to

sharpen any ordinary razor. The guide 26 is provided with ears 71 which rest upon the member 21 when the parts are in the full line position, Fig. 4, thus limiting the downward movement of the guide 26.

70 It will be obvious that many changes in the details of construction may be made without departing from the scope of the invention or of the various claims.

I claim as my invention:

1. A razor-sharpening machine comprising a framework, a pair of rollers adapted to rotate therewithin, means for driving said rollers in opposite directions, a frame slidably mounted in said framework, a blade-holder pivotally mounted in said frame and adapted to present the blade alternately to each of said rollers, an arm secured to said blade-holder, and a slotted member with which said arm coöperates, thereby to rock 80 said blade-holder and to cause the blade contained therein to be presented successively to said rollers, the slot in said member being disposed obliquely to the longitudinal axis of the rollers.

2. A razor-sharpening machine comprising a framework, a pair of rollers adapted to rotate therewithin, means for driving said rollers in opposite directions, a frame slidably mounted in said framework, a blade-holder pivotally mounted in said frame and adapted to present the blade alternately to each of said rollers, an arm secured to said blade-holder, a slotted member with which said arm coöperates, thereby to rock 90 said blade-holder and to cause the blade contained therein to be presented successively to said rollers, means being provided to impart a longitudinal reciprocatory movement to said frame, a shaft, and means whereby 100 said shaft drives both said rollers and said frame reciprocating means, the slot in said member being disposed obliquely to the longitudinal axis of the rollers.

3. A razor-sharpening machine comprising a framework, a pair of rollers adapted to rotate therewithin, means for driving said rollers in opposite directions, a frame slidably mounted in said framework, a blade-holder pivotally mounted in said frame and adapted to present the blade alternately to each of said rollers, an arm secured to said blade-holder, a slotted member with which said arm coöperates, thereby to rock 110 said blade-holder and to cause the blade retained therein to be presented successively to said rollers, a standard by which said slotted plate is adapted to be supported, and means to adjust the height of said slotted plate with 115 respect to said standard, the slot in said member being disposed obliquely to the longitudinal axis of the rollers.

4. A razor-sharpening machine comprising a pair of rollers, a frame adapted to slide parallel to said rollers, a blade-holder 120

4

pivottally mounted upon said frame, a slotted plate, means in connection with said blade-holder and adapted to coöperate with said slotted plate, said means being adapted to 5 be actuated by said slotted plate simultaneously with and because of the longitudinal movement of said frame, a rotating-shaft adapted to cause rotation of said rollers, and means intermediate said shaft and said 10 frame adapted to translate the rotation of

said shaft into longitudinal reciprocation of said frame.

In testimony whereof I have hereunto affixed my name in the presence of two witnesses.

KURT A. VOGEL.
